[57] CLAIM

The ornamental design of a battery charger mounting
bracket, as shown and described.

DESCRIPTION

FIG. 1 is a front perspective view of a battery charger
mounting bracket showing my new design;

FIG. 2 is a right side elevational view thereof, the side
opposite being a mirror image;

FIG. 3 is a top plan view thereof; and

FIG. 4 is a front elevational view thereof.

FIG. 3

FIG. 1

FIG. 2

FIG. 4
